UNITED STATES PATENT OFFICE.

HERMAN NEWTON BURRESS, OF MATEWAN, WEST VIRGINIA, ASSIGNOR OF ONE-HALF TO L. T. COMPTON, OF MATEWAN, WEST VIRGINIA.

SWITCH-THROWING MECHANISM.

Application filed May 13, 1926. Serial No. 108,904.

The invention relates to operating mechanisms for railway switches and has for its principal object to provide a new and improved mechanism of this character which will be easy to operate, will quickly move to one position or the other as occasion may demand, and will permit yielding of the switch tongues away from the rails, under the influence of the wheel flanges, if a train or car is moving in such a direction as to make such yielding essential, either tongue being otherwise tightly held against its respective rail.

With the foregoing in view, the invention resides in the novel subject matter herein-after described and claimed, the description being supplemented by the accompanying drawings.

Fig. 1 is a top plan view with the cover plate of the housing removed.

Fig. 2 is a perspective view showing the mechanism in a different position from that shown in Fig. 1.

Fig. 3 is a detail sectional view on the line 3—3 of Fig. 2.

In the drawings above briefly described, R designates the rails of a track, T has reference to the usual switch tongues and B designates the bridle bar connecting said tongues, the improved switch-throwing mechanism being connected with this bridle bar.

A flat casing 5 having a removable cover 6, is mounted on a plurality of the ties, said casing being preferably inset in said ties, although this is not absolutely essential. Fulcrumed within the casing 5 is a bell-crank 7, one of whose ends is connected by a link 8 and adjustable clevises 9, with the bridle bar B. The other end of this bell crank is preferably widened and is formed with a curved slot 10 which is transverse to and extends laterally in opposite directions from the fulcrum 11 of said bell crank.

A pivotally mounted link 12 is cooperable with one arm of the bell crank 7 in forming a toggle for actuating said bell crank to throw the switch. In the present showing, one end of this link is bifurcated to straddle the slotted portion of the bell crank 7 and carries a roller or other shoe 13 which is slidably received in the slot 10. Means are provided to cause quick movement of this link 12 so that its shoe 13 moves to one end or the other of the slot 10, after

said link has been moved with respect to the bell crank, to a dead-center position, that is, to a position in which the shoe 13 is disposed upon an imaginary line drawn from the fulcrum 11 to the pivot 14 of the link. When this dead-center position is reached, the means just referred to, comes into play to snap the link beyond the dead-center position and at the same time exerts such force on the link, as to cause the latter to swing the crank 7 to a switch-operating position. In the preferred construction, the pivot 14 connects the link 12 with an arm 15 which is pivoted in the casing at 16, any suitable spring device 17 within said casing, being connected with the arm for exerting the necessary force upon the link 12. 18 merely designates a rest upon which one end of the arm 15 slides. This rest and all studs by means of which movable parts are connected with the bottom of the casing 5, may well be integral with or otherwise rigidly joined to said bottom.

A shifting bar 19 is provided for the link 12, said shifting bar being transverse to said link and having a combined pivotal and sliding connection therewith. This connection preferably comprises a roller or shoe 20 between the furcations of the link 12, and a slot 21 in the bar 19. For a purpose to appear, two coiled, tension springs 22, or their equivalents, are connected with the bar 19 at two relatively fixed points, said springs being disposed at opposite sides of the shoe 20 and being suitably anchored to the casing 5.

The end of the shifting bar 19, remote from the connection 20—21, is provided with a roller or other shoe 23, and a pivoted actuator 24 is co-operable with this shoe, the pivot of said actuator being indicated at 25. This actuator is in the form of a plate, in the present disclosure, and it is formed with an elongated opening 26 which extends in opposite directions from the pivot 25, one end of said opening having a bar-pushing seat 27 while the other end of said opening is formed with a bar-pulling seat 28, either of said seats being adapted to receive the shoe 23.

A rod 29 is shown leading to an appropriate switch stand 30 for operating the actuator 24, said stand having a hand lever or other desired control 31. A spring 32 is preferably employed to return this lever to

its initial position after each actuation thereof, and another spring 33 may be connected with the actuator 24 for the same purpose, a suitable stop 34 being provided in the casting 5 to limit the return movement of the actuator after release of the lever 31. If desired, a guiding yoke 35 may be provided for the lever 31 having appropriate stops for limiting the swing of said lever, one of these 10 stops being disclosed at 36 in Fig. 2, from which view, it will be understood that the lever is resting against and obscuring the other stop.

Assuming the parts stand as shown in Fig. 15 1 and the switch is to be thrown to its other position, the operation is as follows: The lever 31 is moved toward the opposite end of the guide 35, thus pulling upon the rod 29 and causing the actuator 24 to force upon 20 the shifting bar 19, the shoe 23 of this bar being then received in the bar-pushing notch or seat 27. This movement of bar 19 causes one end of the slot 21 to thrust against the shoe 20, thus swinging the link 12 toward a 25 dead-center position, and during this movement, the spring 17 is tensioned by the outward force which the link exerts upon the arm 15. The result is that as soon as the link 12 reaches the aforesaid dead-center position, the spring device 17 comes into play 30 to quickly throw said link beyond said position, so that the link 12 and the slotted portion of the bell crank 7, then act as a toggle and under the influence of the device 17, 35 quickly throw the switch to its reversed position.

Swinging of the link 12 in the manner just set forth, causes its shoe 20 to move to the opposite end of the slot 21, so that the 40 left-hand spring 22 of Fig. 1 is pulling upon the bar 19 a greater distance from the shoe 20, than the right-hand spring 22. The result is that as soon as lever 31 is released and the shoe 23 can disengage from the seat 27, 45 the left-hand spring 22 will reverse the position of the bar 19, that is, swing it so that its shoe 23 will seat in the notch or seat 28, as shown in Fig. 2. It will thus be seen that the mechanism is now set for again moving 50 the switch to its previous position. Reference being now made to Fig. 2, it will be seen that the next operation of the lever 31 will swing the actuator 24 so as to cause the co-acting seat 28 and shoe 23 to pull upon the 55 shifting bar 19. This bar will then swing the link 12 toward a dead-center position and the movement of the link and consequent movement of the arm 15 will again place the spring device 17 under tension. 60 As soon as this dead-center position is reached, the device 17 comes into play to cause rapid snapping of the link 12 past dead-center, and the link and slotted portion of the bell crank 17 then again act as a 65 toggle to quickly throw the switch. This

movement of parts disposes the shoe 20 again at the inner end of the slot 21, so that the left-hand spring 22 of Fig. 2 will have more swinging force upon the shifting bar 19, than the right-hand spring. The result is 70 that as soon as lever 31 is released and the actuator 24 returns to its normal position, said left-hand spring will swing the lever 19 until its shoe 23 is seated in the bar-pushing seat 27, as seen in Fig. 1, the mechanism being 75 then set for further operation.

If desired, the bell crank 7 may carry a contact 37 co-operable with relatively stationary contacts 38 and 39 to operate an appropriate signal and disclose the position of 80 the switch.

The novel construction shown and described is rather simple and inexpensive, yet will be efficient and in every way desirable, 85 and as excellent results may be obtained from the details disclosed, they may well be followed. However, within the scope of the invention as claimed, various modifications may be made.

1 claim:-

1. A switch throwing mechanism comprising a lever and means for connecting it to a switch tongue, a pivotally mounted link having a shoe at one end, said lever having a curved slot which slidably receives said shoe and extends in opposite directions from an imaginary line between the lever fulcrum and the link pivot, means acting longitudinally on said link to quickly snap it beyond a dead-center position when the link is 100 moved to such position, said means being then active to move the link and lever to a switch-throwing position, and means for moving said lever to said dead-center position. 105

2. A switch throwing mechanism comprising a lever and means for connecting it to a switch tongue, a pivotally mounted link having a shoe at one end, said lever having a curved slot which slidably receives said shoe and extends in opposite directions from an imaginary line between the lever fulcrum and the link pivot, means acting longitudinally on said link to quickly snap it beyond a dead-center position when the link is 115 moved to such position, said means being then active to move the link and lever to a switch-throwing position, a shifting bar for said link extending transversely thereof and having a combined sliding and pivotal connection therewith, and means for either pushing or pulling said bar according to the direction in which said link is to be moved. 120

3. A switch throwing mechanism comprising a lever and means for connecting it to a switch tongue, a pivotally mounted link having a shoe at one end, said lever having a curved slot which slidably receives said shoe and extends in opposite directions from an imaginary line between the lever fulcrum 125 and the link pivot, means acting longitudinally on said link to quickly snap it beyond a dead-center position when the link is moved to such position, said means being then active to move the link and lever to a switch-throwing position, and means for either pushing or pulling said bar according to the direction in which said link is to be moved. 130

- and the link pivot, means acting longitudinally on said link to quickly snap it beyond a dead-center position when the link is moved to such position, said means being 5 then active to move the link and lever to a switch-throwing position, a shifting bar for said link extending transversely thereof and having a combined sliding and pivotal connection therewith, said shifting bar having 10 a shoe at a point spaced from said link, a pivotally mounted actuator for said shifting bar, said actuator having an elongated opening which extends in opposite directions beyond its pivot and receives said shoe, 15 the ends of said opening being formed with a bar-pushing seat and a bar-pulling seat respectively, both adapted to receive said shoe of the shifting bar, and position-reversing means for said shifting bar active 20 to swing it automatically from one end of said opening to the other after said link swings upon its pivotal mounting.
4. In a switch throwing mechanism, a lever having a curved slot transverse to its fulcrum and extending in opposite direc- 25
- tions from the same, a pivotally mounted link having a shoe slidable in said slot, and means acting longitudinally on said link for rapidly snapping said link in either direction along said slot from a neutral position 30 and for then exerting a moving force on said lever.
5. In a switch throwing mechanism; a pivotally mounted link for movement to either of two positions, a shifting bar for 35 said link extending transversely thereof and having a combined pivotal and sliding connection therewith, and spring means active at relatively fixed points on said bar at opposite sides of said connection, for the purpose set forth.
6. In a switch throwing mechanism; a pivotally mounted actuator having an elongated opening which extends in opposite directions from its pivotal axis, the ends of 40 said opening having oppositely facing seats.

In testimony whereof I have hereunto affixed my signature.

HERMAN NEWTON BURRESS.
